UNITED STATES PATENT OFFICE.

WILLIAM M. CHRISTOPHER, OF AMSTERDAM, NEW YORK.

BROOM.

1,329,826.

Specification of Letters Patent.

Patented Feb. 3, 1920.

Application filed May 2, 1918. Serial No 232,081.

To all whom it may concern:

Be it known that I, WILLIAM M. CHRISTOPHER, a citizen of the United States, residing at Amsterdam, in the county of 5 Montgomery and State of New York, have invented certain new and useful Improvements in Brooms, of which the following is a specification, reference being had therein to the accompanying drawing.

10 The present invention relates to brooms and, more particularly, to improved means for securing a detachable broom head to its handle.

The invention consists of the combination 15 with the handle, broom head, and a two-part holder for attaching the broom head to the handle, of which an improved bolt, nut, and spring-link handle, appearing more fully hereinafter and set forth in the appended claims.

In the drawings,

Figure 1 is a perspective view of my improved construction of broom.

Fig. 2 is a vertical section through the 25 holder, the head being partly in section.

Fig. 3 is a perspective view of the nut and the link carried thereby; and

Fig. 4 is a detail view partly in section showing a modified form of head.

30 Like numerals of reference refer to like parts in the several figures of the drawing.

In the drawing 1 indicates the broom proper or head having the broom straw secured around the core 2 by split rings 3 which are spaced, as clearly shown, in order to form a pair of annular projections or ribs. These rings are placed in position 35 upon the core under pressure, so as to bind the broom straw.

40 My improved construction of holder comprises a pair of duplicate members 4 and 5 provided with overlapping apertured ears 6, which are secured to the broom handle 7 by rivet 8 in such a manner that these mem-

bers are free to swing on the pivot in order 45 to separate the members. The members 4 and 5 are substantially U-shaped in cross section, and are provided with enlarged lower ends having annular spaced ribs 9,

50 forming on their inner faces annular grooves adapted to receive the annular projections formed by the rings 3 when the two members of the holder are brought together, as shown in Figs. 1 and 2. These members are 55 formed of sheet metal stamped to provide the annular ribs and are reinforced by

forming longitudinal ribs 10. By stamping the members 4 and 5 to provide the grooves the grooves are formed substantially semi-circular in shape. The upper portions of 60 the members 4 and 5 snugly engage the lower end of the handle 7, which handle is split longitudinally, as shown at 11, in order to allow the members to be drawn together around the head.

65 One of the members is provided with a square opening 12 to receive the head 13 of a bolt 14, and the other member is provided with an opening 15 to receive a tubular nut 16 which works on the bolt 14, and is provided with a head 17 having a pair of spaced ears 18, the outer walls of which are provided with spaced grooves 19. These ears are apertured, as shown at 20, in which the free ends of the spring link 21 are pivotally mounted in such a manner that when the link is moved outwardly into the grooves 19, it will be held so as to form a handle in order to allow the nut to be rotated so as to bind the two members of the holder over the 75 head.

70 The ears 18 are also provided with grooves 22 to receive the spring link in order to hold the same in a plane parallel with the holder and in the form shown, the 75 holder is cut away, as shown at 23, in order to allow the free end of the link to engage the wooden handle.

75 In the modification shown in Fig. 4, the head 1' is provided with a sheet metal ring 90 24 having a pair of spaced annular ribs 25 adapted to fit within the grooves of the holder, and it will be seen that by this construction the head will be provided with spaced annular projections.

80 From the foregoing description it will be seen that I have provided a broom which is provided with a novel form of head to receive a holder carried by a handle, which allows the holder and head to be quickly 100 connected or disconnected, and by constructing a broom in this manner, when the head is worn out, a new head can be readily placed in position within the holder.

I claim:

85 1. In a broom, the combination of a broom head, a handle, a two-part holder connected to the handle and also clamping the broom head and thereby detachably securing it to the handle, a bolt and nut connecting the 110 two parts of the holder together and causing them to clamp the broom head, said nut

105

110

having locking means, and a spring link handle pivoted to the nut and adapted to be either folded alongside the handle, or, to be swung outwardly for use in turning the nut, said locking means on the nut serving to hold the spring link in either folded or extended position.

2. In a broom, the combination of a broom head, a handle, a two-part holder connected to the handle and also clamping the broom head and thereby detachably securing it to the handle, a bolt and nut connecting the two parts of the holder together and causing them to clamp the broom head, said nut having ears provided with grooves,

and a spring link handle of bail-shape whose ends are pivoted to said ears, said spring link being adapted to be either folded alongside the handle or swung outwardly for use in turning the nut, the aforesaid grooves receiving and holding the parts of the spring-link handle when the latter is either in folded or extended position. 20

In testimony whereof I hereunto affix my signature in the presence of two witnesses. 25

WILLIAM M. CHRISTOPHER.

Witnesses:

FRED WATERMAN, Sr.,

HARRISON C. ABELING.
